[57] CLAIM

The ornamental design for a battery charger, as shown and described.

DESCRIPTION

FIG. 1 is a top plan view of a battery charger embodying our new design;
FIG. 2 is a right side elevational view thereof;
FIG. 3 is a front elevational view thereof;
FIG. 4 is a rear elevational view thereof;
FIG. 5 is a bottom plan view thereof;
FIG. 6 is a left side elevational view thereof;
FIG. 7 is a right perspective view thereof on a reduced scale;
FIG. 8 a top plan view of a battery charger showing a second embodiment of our new design; and,
FIG. 9 is a right perspective view thereof.
